UNITED STATES PATENT OFFICE.

JOHN EDMAN, OF MINNEAPOLIS, MINNESOTA, ASSIGNEE, BY DIRECT AND MESNE ASSIGNMENTS, TO EDMAN CAR DOOR COMPANY, OF MINNEAPOLIS, MINNESOTA, A CORPORATION OF MINNESOTA.

GRAIN-DOOR FOR CARS.

1,261,108.

Specification of Letters Patent.

Patented Apr. 2, 1918.

Application filed July 25, 1912. Serial No. 711,497.

To all whom it may concern:

Be it known that I, JOHN EDMAN, a citizen of the United States, residing at Minneapolis, in the county of Hennepin and State of Minnesota, have invented certain new and useful Improvements in Grain-Doors for Cars; and I do hereby declare the following to be a full, clear, and exact description of the invention, such as will enable others skilled in the art to which it appertains to make and use the same.

This invention has for its object to provide an improved side door for cars, capable of use as a grain door and for other purposes, and by the use of which, the customary outside door is made unnecessary.

Particularly, the invention is in the nature of an improvement of that type of car door disclosed and claimed in my prior Patents, 865,775, of date, June 11, 1907, 884,011, of April 7, 1908, and 901,959, of date, October 27, 1908.

Generally stated, the invention consists of the novel devices and combinations of devices hereinafter described and defined in the claims. Particularly, the invention is directed to the modification or improvement on the door above noted; whereby the door is adapted to be swung outside of the car and then slid along the exterior of the car, out of line with the door opening which it is adapted to close. The invention, however, also, involves other important features of novelty.

The invention is illustrated in the accompanying drawings wherein like characters indicate like parts throughout the several views. Referring to the drawings,

Figure 1 is a view in side elevation with some parts broken away, showing the improved door applied to one of the side door openings of an ordinary box car;

Fig. 2 is a transverse vertical section taken approximately on the line $x^2 x^2$ on Fig. 1, some parts being broken away;

Fig. 3 is a horizontal section taken on the irregular line $x^3 x^3$ on Fig. 4, some parts being broken away; and

Fig. 4 is a vertical section taken approximately on the irregular line $x^4 x^4$ on Fig. 2, some parts being broken away.

The numeral 1 indicates an ordinary box car body having at its sides the usual door openings formed between posts 2. Rigidly

secured on the opposing faces of the posts 2 are vertically extended stop strips 3 that are preferably extended from bottom to the tops of said posts.

The main door 4, which is preferably a sheet metal structure properly reinforced and stiffened, is made of a size to fit within the door opening, but at its upper central portion it is cut away and therein provided with two supplemental door sections 5 and 6. The supplemental door section 5 is, at its lower edge, connected to the main door 4 by hinges 7, so that it is adapted to be turned downward against the inner face of the said door. The supplemental door 6, however, is adapted to be moved upward and entirely separated from the main door, and for such purpose it is provided with long trunnions 8 that project beyond the edges thereof, and at their ends are equipped with anti-friction rollers 9 that work in curved guideways 10, rigidly secured to the inner faces of the door posts 2 and to the roof structure of the car. Preferably, and as shown, the guideways 10 are formed with extensions or lateral projections of the stop strips 3. The lower edge of the supplemental door 6 is provided with depending joint strips 11 that are adapted to overlap the upper edge of the supplemental door 5, as shown in Fig. 2, thus forming a grain tight joint therewith. Secured on top of the door frame and extending across the door opening, is a joint strip 12 against which the upper edge of the supplemental door 6 and the upper ends of the bifurcated upper portion of the main door 4 are normally seated, overlapping the same so as to form a tight joint.

When the door is in operative position, the main body portion 4 thereof is forced inward and seated against the stop strips 3, thereby forming grain tight joints at the side edges of the door. The numeral 13 indicates hand pieces which are preferably applied to the lower portion of the main door 4. Located on the outside of the car and extended over the doorway, and for a distance greater than the width of the doorway at one side of said doorway, is an oscillatory track bar or rail 14 having trunnions 14^a at its ends, journaled in bearings 15 secured on the upper portion of the side of the car. The alined axes of these trunnions are located considerably outward of

the sides of the car, so as to permit the car door to be dropped into a position shown by dotted lines in Fig. 2, all as will hereinafter more fully appear.

5 The lower portion of this oscillatory track bar 14 is a hollow structure that is rectangular in cross section, so that anti-friction rollers or wheels 16 are adapted to run therein. As shown, the central portions of 10 the roller 16 are reduced to afford spindles on which the upper ends of hanger clips 17 are hung. These hanger clips 17 work through longitudinal slots in the bottoms of the track bars 14 and, as shown, are secured 15 at their projecting lower ends to a hanger bar 18, to which the upper ends of a pair of hanger links 19 are rigidly secured. The lower ends of these hanger links 19 are, as shown, laterally bent and pivotally 20 mounted in hinge lugs 20, shown as secured on the sides of the bifurcated upper portion of the main door 4. In Fig. 2, the oblique position of the hanger links 19 when the door is in operative position, is indicated by 25 full lines, and the vertical position thereof, when the door is swung outward into inoperative position, is indicated by dotted lines.

For securing the door in a closed or operative position, I employ so-called lock blades 21 located, one at each side of the door opening, and provided at their upper and lower ends with trunnions 22, seated in suitable bearings 23 secured to the adjacent 30 door posts 3. The trunnions 22 are so located that when the lock blades 21 are turned outward, the door 4 may swing laterally outward between the same. When, however, the lock blades 21 are turned toward 35 each other, they overlap the edges of the door 4 and hold the same seated against the stop strips 3. The lock blades 21 are adapted to be held in operative positions by lock bars 24 pivoted at their outer ends to 40 the said blades 21, and at their free ends engageable with the laterally offset upper end of a lock bracket or block 25 that is rigidly secured to the central portion of the door 4. When the free ends of the lock bars 45 24 are interlocked with the said bracket 25, as shown in Fig. 1, the lock blades 21 are held against outward swinging movements and are thereby caused to positively hold the door 4 in its operative or closed position. The free ends of the lock bars 24 may be 50 disengaged from the bracket 25 by directly taking hold thereof and pressing the same upward, but the operation is made easier by the use of a holding flange 26 seated in 55 the bracket 25 with its head directly under the free ends of the said lock bars, and adapted to be moved upward to simultaneously release the said lock bars. Intermediate pivoted to the central portion of the 60 door 4 at 27 is a lock lever 28, which, at its

lower end is provided with a flanged head 29 which, when turned downward, overlaps the free ends of the lock bars 24 and positively holds the same interlocked to the bracket 25. The lower end of this lock lever 28 is provided with a vertically movable lock bolt 30 adapted to be held by gravity, engaged through a perforation in the flanged upper end of the bracket 25, to thereby positively hold the lock lever 28 in an operative position shown in Fig. 1. This lock bolt 30 is provided with a finger piece 31 by means of which it may be vertically moved, and its depending lower end will preferably be slotted so that the car seal may be applied thereto. At its upper end, the lock lever 28 is provided with a hook 32 that is adapted to be interlocked to a lug 33 on the lower edge of the supplemental door 6, to thereby lock the said door 6 in an operative position. Thus it will be seen that primarily, the lock bolts 30 lock the lever 28 in an operative position; that the lock lever 28 locks the supplemental door 6 and the lock bars 24 in operative positions; that the lock bars 24 70 secure the lock blades 21 in operative positions; and finally, that the said blades 21 secure the main door 4 in its operative or closed position. Hence, a seal being applied to the lower end of the bolt 30 prevents all 75 of the said parts from being moved from their operative positions without breaking the seal. The numeral 34 (see Fig. 1) indicates a stop upon which the upper end portion of the lever 28 will rest when the said lever is turned into an approximately horizontal inoperative position.

To throw the main door with its supplemental section 5 into an inoperative outwardly movable position indicated by dotted lines in Fig. 2, it is only necessary to take hold of one or both of the hand pieces 13 and to pull the lower end of the main door 4 outward so that it will clear the doorsill. This being done, the door will swing by 100 gravity into the position shown by dotted lines in Fig. 2, and it may then be slid along the outer side of the car to a position indicated by dotted lines in Fig. 1, where it leaves the doorway entirely open.

To replace the door, the upper edge is forced laterally inward and the hanger links 19 will slightly raise the upper edge thereof, so that it will be engaged back of the lower edge of the joint strip 12, and then the lower edge of the said door is forced over the door sill into operative position. Then the door should be locked by means of the lock blades 21 and coöperating devices, all as before fully described.

I also provide means whereby a person standing on the ground at one side of the car may easily cause a movement of the supplemental door 6 to and from operative position. This device, as shown, comprises a

vertical shaft 35 mounted in suitable bearings on the side of the car adjacent to one of the door posts, and provided at its lower end below the bottom of the car with an operating lever 36. At its upper end, the rod 35 is provided with an arm 37, to which one end of a chain 38 is attached. This chain 38 is passed over guide sheaves 39 and 40, mounted on an angle beam 41, secured by the roof structure and to which, as shown, the upper ends of the guide channels 10 are attached. The other end of this chain 38 is attached to the upper portion of the supplemental door 6. When the lever 36 is moved into one extreme position, the supplemental door 6 has been caused to run upward on the guide channels 10 into an inoperative position indicated by dotted lines in Fig. 2, and when the said lever 36 is moved into its other extreme position, the said supplemental door will run by gravity into an operative position.

Obviously, the main door 4 and its supplemental hinge section 5 may be secured in operative or closed position while the supplemental door 6 is in an inoperative position, thereby leaving an opening through the doorway through which grain, coal, or other materials may be loaded into the car through a spout, or otherwise. When the supplemental door 6 is also closed, the entire doorway is completely and tightly closed.

This improved door, as is evident, serves all of the functions performed by the ordinary side door and by a grain door, and has in fact, a greater range of utility than the said other two doors combined. It is adapted to be very easily and quickly operated and is very strong and durable.

What I claim is:

1. The combination with a car body having a side door opening, of a main door for said door opening, means supporting said main door for lateral swinging and endwise sliding movements to and from operative position, means for securing said main door in an operative position in said door opening, a supplemental door, said main door having an opening extending from its upper edge, the sides of which are engaged by said supplemental door, and curved guides for said supplemental door extending upward to the roof structure of the car body.

2. The combination with a car body, having a side door opening, of a track extended along the outer side of the car body above the door opening and to one side of the door opening, and having at its ends supporting pivots located above its track surface whereby it is mounted to freely swing laterally and tends to assume a downward position, a door adapted to open and close said door opening, and a door hanger mounted to travel on said track and to partake of common oscillatory movements therewith, said door hanger having depending portions pivotally connected to said door and arranged to support the same in an open position at one side of the car, free for traveling movements therewith to and from alinement with said door opening.

In testimony whereof I affix my signature in presence of two witnesses.

JOHN EDMAN.
